UNITED STATES PATENT OFFICE.

PAUL MAIWURM, OF SAN DIEGO, CALIFORNIA.

BEVERAGE DISPENSER.

Application filed April 29, 1925. Serial No. 26,653.

My invention relates to a beverage dispenser, and the objects of my invention are: First, to provide a dispenser of this class whereby the beverages or drinks adapted to 5 be dispensed are displayed in transparent containers through an open portion in the front wall of the supporting cabinet; second, to provide a dispenser of this class having a beverage or drink display cabinet 10 provided with a plurality of dispensing cocks or faucets arranged at the front side below the beverage or drink containers and also provided with openings contiguous to the cocks or faucets for depositing used cups 15 into the bottom of the cabinet; third, to provide a liquid dispenser having a plurality of mixed liquid containers from which the mixed liquids are adapted to be drawn as desired and which are continuously re- 20 supplied with similar mixed liquids as the same is withdrawn from the mixed liquid display containers connected with unmixed 25 liquid supply containers for supplying said display containers with the unmixed liquids in proper proportions, which unmixed liquids are mixed before being discharged into the display containers as the liquids 30 therein are periodically withdrawn; fifth, to provide a beverage dispenser having a plurality of mixed drink containers which, as the drinks therein are periodically withdrawn, are supplied from a single float valve 35 controlled water tank connected to a continuous source of supply, and by readily re- 40 fillable syrup storage containers, the water and syrup being mixed in certain proportions at the upper ends of the mixed drink containers as the water and syrup are dis- 45 charged therein by the vacuum produced by the withdrawal of the mixed drinks from said containers; sixth, to provide a drink dispenser having mixed drink storage con- 50 tainers supported at the upper portion of a containing cabinet and unit cooling means at the lower portion of the cabinet connected with the respective containers and from which cooling means the mixed drinks are 55 discharged through cocks or faucets for consumption; seventh, to provide a cabinet for a dispenser of this class at the upper portion of which are supported the display and storage containers and tanks, and at the lower portion of which is provided a backwardly 60 extended ice chamber for cooling the liquids, 65 the ice chamber serving as a support for the operator for refilling the containers or tanks without disturbing the customers or the front of the dispenser in any way; eighth, to provide as a whole a novelly constructed beverage dispenser, and ninth, to provide a dispenser of this class which is simple and economical of construction proportionate to its functions, durable, compact, easily oper- 70 able, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the 75 characters of reference thereon, which form a part of this application, in which:

Figure 1 is a front elevational view of my beverage dispenser; Fig. 2 is a sectional elevational view thereof, taken through 2—2 80 of Fig. 1, showing certain parts and portions thereof in elevation to facilitate the illustration; Fig. 3 is a sectional view thereof in plan, taken through 3—3 of Fig. 2, showing certain parts and portions broken away and 85 in section to facilitate the illustration, and Fig. 4 is a rear view of the unit water tank with the back wall thereof removed, showing certain portions thereof in section and the 90 connections thereto fragmentarily.

Like characters of reference refer to similar parts and portions throughout the several views of the drawings.

The cabinet 1 of my beverage dispenser is 95 provided at the upper portion of its front side with openings 1^a, at or behind which openings is positioned a corresponding number of vertically positioned, large, transparent, mixed-drink display containers 2. Said containers 2 are hermetically sealed 100 at their upper ends by means of covers 3, which are secured against the upper open ends of said containers in any convenient manner such as by bolts, shown in Figs. 2 and 3. Said containers may be supported 105 at their lower ends on a support 4, as shown in Fig. 2. At the back side of the containers 2 and near the lower ends thereof is positioned a long water tank 5 for supplying water to all of the containers 2. Said water tank may also be supported on the support 110 4 as shown. The tank is connected, by means

of the pipe 6, with a continuous water supply such as a city main. Within the tank 5 is provided a float controlled valve 7 for constantly retaining the water in said tank at a predetermined level, the valve controlling mechanism being shown best in Fig. 4. On the water tank 5 is supported a plurality of syrup jars or containers 8, also preferably transparent, there being provided one syrup jar 8 for each of the mixed drink containers 2. The containers 8 are provided with covers 9 having separate, readily removable, smaller covers 9^a for refilling the containers 8. Each of the containers 2 communicate by means of a conductor 10 with the lower portion of the water tank 5, said conductors extending through the covers 3 of the containers 2. The conductors 10 are provided at their lower ends, extending into the water tank 5, with ball check valves 12 to prevent the return of the water from the conductors 10 back into the water tank 5. Each of the mixed drink containers 2 similarly communicates, by means of conductors 11, with their respective syrup storage containers 8, the lower ends of the conductors 11 extending into the containers 8 being similarly provided with ball check valves 13 to prevent the return of the syrup in the conductors 11 to the containers 8. Said conductors 10 and 11 are provided at their ends extending through the covers 3 with caps 14 and 15, respectively, said caps being provided with discharge orifices of such size as to provide for the discharge of the syrup in the containers 8 and the water in the tank 5 into the containers 2 in the proportion of one to four, the orifices in the caps 14 and 15 being also dependent directly on the relative viscosities of the water and the syrup. Within the containers 2 at their upper ends are provided drink mixing members 16, preferably in the form of funnels which are secured to the inner sides of the covers 3.

At the lower rear portion of the cabinet 1 is provided a long insulated ice container 17 provided with a readily removable cover 18. This cover 18 also serves as a walk or supporting platform for the operator when filling the syrup storage containers 8 from the back side of the cabinet without interfering in any way with the customers or the dispensing operation of the dispenser. In the ice chamber 17 is positioned a plurality of cooling coils 19, there being provided one of such coils for each mixed drink display container 2. The upper ends of said coils are connected, by means of conductors 20, with the lower ends of the containers 2, while the lower ends of said coils are connected, by means of conductors 21, with dispensing cocks or faucets 22 positioned directly below the containers 2 within a recess 1^b built inwardly from the front side of the cabinet 1.

In the rear wall of the recess 1^b of the

cabinet 1 is provided a plurality of openings 1^c which communicate with the lower end of the cabinet in which is positioned a used cup receptacle 23 for receiving the used cups deposited therein through the openings 1^c. 70

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims. 75

Having thus described my invention, what I claim as new and desire to secure by Letters Patent is:

1. In a liquid dispenser, a supporting means, an hermetically sealed mixed-liquid container supported thereby, a diluting-liquid supply tank positioned at the one side near the lower end of said mixed-liquid container, a concentrated-liquid container positioned contiguous to said first mentioned container, conductors communicating with the lower portions of said tank and said concentrated-liquid container and with the upper end of said mixed-liquid container, and check valves at the ends of said conductors extending into said tank and said concentrated-liquid container, said conductors being provided at their ends extending into said mixed-liquid container with orifices adapted to permit the discharge of the liquid in said tank and said concentrated-liquid container to be discharged into said mixed-liquid container in definite predetermined proportions. 90 95

2. In a liquid dispenser, a supporting means, an hermetically sealed mixed-liquid container supported thereby, a diluting-liquid supply tank positioned contiguous to said mixed-liquid container, a concentrated-liquid container also positioned contiguous to said mixed-liquid container and to said tank, conductors extending into said tank and said concentrated-liquid container and communicating with said mixed-liquid container, said conductors being provided at their ends extending into said mixed-liquid container with orifices adapted to permit the discharge of the liquid in said tank and said concentrated-liquid container to be discharged into said mixed-liquid container in definite predetermined proportions, a cooling chamber positioned at the lower end of said supporting means, a mixed-liquid, cooling means positioned in said cooling chamber and connected with the lower end of said mixed-liquid container, and a mixed-liquid dispensing cock positioned below said mixed-liquid container and connected with said mixed-liquid cooling means. 110 115 120 125

3. In a beverage dispenser, a plurality of mixed drink containers arranged vertically 130

and contiguous to each other, a long water tank positioned behind and at the lower portions of said mixed drink containers, a plurality of syrup containers positioned on said water tank, one behind each of said mixed drink containers, conductors connecting the lower portions of said water tank and said syrup containers with the upper ends of each of said mixed drink containers, and check valves at the ends of said conductors extending into said water tank and into said syrup containers.

4. In a beverage dispenser, a plurality of mixed drink containers arranged vertically and contiguous to each other, a long water tank connected with a source of water supply positioned behind and at the lower portions of said mixed drink containers and provided with a predetermined water level control valve for supplying water to said tank from said source, a plurality of syrup containers positioned on said water tank, one behind each of said mixed drink containers, conductors connecting the lower portions of said water tank and said syrup containers with the upper ends of each of said mixed drink containers, and check valves at the ends of said conductors extending into said water tank and into said syrup containers, said conductors being provided at their ends extending into said mixed drink containers with orifices of such a size as to provide for the discharge of the water from said tank and the syrup from said syrup containers into said mixed drink containers in definite predetermined proportions.

5. In a beverage dispenser, a plurality of mixed drink containers arranged vertically and contiguous to each other, a long water tank positioned behind and at the lower portions of said mixed drink containers, a plurality of syrup containers positioned on said water tank, one behind each of said mixed drink containers, conductors connecting the

lower portions of said water tank and said syrup containers with the upper ends of each of said mixed drink containers, check valves at the ends of said conductors extending into said water tank and into said syrup containers, and a syrup and water mixing means in connection with said conductors.

6. In a beverage display and mixing dispenser, a cabinet, a plurality of transparent containers positioned in said cabinet at its upper portion and exposed to view, discharge faucets arranged at the front side of said cabinet below said containers and communicating therewith, supply tanks positioned at the back side of said display containers and communicating therewith, a beverage cooling means arranged at the lower portion of the back side of said cabinet, and conductors connecting said display containers with said beverage cooling means and said faucets with said cooling means, said beverage cooling means serving as a platform for the operator for filling said supply tanks without interfering with the operation of said dispenser at the front thereof.

7. In a beverage dispenser, an hermetically sealed mixed drink container, a diluting liquid container, a concentrated liquid container, conductors connecting the lower portions of said diluting liquid container and said concentrated liquid container with the upper end of said mixed drink container, check valves at the ends of the conductors extending into said diluting liquid container and concentrated liquid container, a faucet connected with said mixed drink container adapted, when open, to draw liquids through said conductors into said mixed liquid container.

In testimony whereof, I have hereunto set my hand at San Diego, California, this 21st day of April, 1925.

PAUL MAIWURM.
